United States Patent

Des. 241,478
Patented Sept. 14, 1976

241,478

COMB

Anthony R. Romani, Hollidaysburg, Pa. (c/o Antonio's Manufacturing Inc., P. O. Box 1803, Altoona, Pa. 16603)

Filed Mar. 5, 1974, Ser. No. 448,278

Term of patent 14 years

Int. Cl. D28—03

U.S. Cl. D86—8

FIG. 1 is a side elevational view of the comb, it being understood that the opposite side is a mirror image of the view shown in FIG. 1;

FIG. 2 is a top plan view of the comb shown in FIG. 1;

FIG. 3 is a bottom or tooth end view of the comb as shown in the FIG. 1 elevation;

FIG. 4 is an elevational view of the tooth end of the comb shown in FIG. 1; and

FIG. 5 is a handle end elevational view of the comb shown in FIG. 1.

I claim:

The ornamental design for a comb, as shown and described.
